CLAIM

The ornamental design for a boat fender, as shown and described.

DESCRIPTION

FIG. 1 is a front perspective view of a first embodiment of a boat fender;

FIG. 2 is a front view of the design of FIG. 1;

FIG. 3 is a top view of the design of FIG. 1, the bottom view being substantially identical thereto;

FIG. 4 is a right side view of the design of FIG. 1, the left side view being substantially identical thereto;

FIG. 5 is a front perspective view of a second embodiment of a boat fender;

FIG. 6 is a front view of the design of FIG. 5;

FIG. 7 is a top view of the design of FIG. 5, the bottom view being substantially identical thereto;

FIG. 8 is a right side view of the design of FIG. 5, the left side view being substantially identical thereto;

FIG. 9 is a front perspective view of a third embodiment of a boat fender;

FIG. 10 is a front view of the design of FIG. 9;

FIG. 11 is a top view of the design of FIG. 9, the bottom view being substantially identical thereto;

FIG. 12 is a right side view of the design of FIG. 9, the left side view being substantially identical thereto;

FIG. 13 is a front perspective view of a fourth embodiment of a boat fender;

FIG. 14 is a front view of the design of FIG. 13;

FIG. 15 is a top view of the design of FIG. 13, the bottom view being substantially identical thereto; and,

FIG. 16 is a right side view of the design of FIG. 13, the left side view being substantially identical thereto.

The broken lines illustrate portions of the boat fender that form no part of the claimed design.
